DESIGN FOR A DRAFT ARM

Sherburne D. Levings, Winnetka, Ill., assignor to
The Bastian-Blessing Company, Chicago, Ill.,
a corporation of Illinois

Application April 11, 1941, Serial No. 100,326

Term of patent 14 years

(Cl. D2—3)

To all whom it may concern:

Be it known that I, Sherburne D. Levings, a citizen of the United States, residing at Winnetka, in the county of Cook and State of Illinois, have invented a new, original, and ornamental Design for a Draft Arm, of which the following is a specification, reference being had to the accompanying drawing, forming a part thereof.

Figure 1 is a side elevational view of a draft arm, showing my new design; and

Figure 2 is a bottom plan view of the nozzle element of the draft arm shown in Fig. 1.

The dominant feature of my design resides in the nozzle element of the draft arm, shown in full lines.

I claim:

The ornamental design for a draft arm, as shown and described.

SHERBURN D. LEVINGS.
